Patented Mar. 23, 1920.

FIG. 4.

Orris Thompson, Inventor

By *Geo. P. Kimmel*
Attorney

UNITED STATES PATENT OFFICE.

ORRIN THOMPSON, OF NEENAH, WISCONSIN.

PHONOGRAPH NEEDLE OR STYLUS SHARPENER.

1,334,818.

Specification of Letters Patent. Patented Mar. 23, 1920.

Application filed December 10, 1918. Serial No. 263,094.

To all whom it may concern:

Be it known that I, ORRIN THOMPSON, a citizen of the United States, residing at Neenah, in the county of Winnebago and State 5 of Wisconsin, have invented certain new and useful Improvements in Phonograph Needle or Stylus Sharpeners, of which the following is a specification.

This invention relates to improvements 10 in phonograph accessories and it is the principal object of the invention to provide a novel phonograph needle or stylus sharpener capable of being used to efficiently sharpen and polish phonograph needles or styluses 15 formed of fiber, wood, composition or other substance and to cause the accurate reproduction, with the use of reproducing mechanism, of the sound waves on a record, thus lengthening the period of time for which 20 these devices can be ordinarily used and in consequence, effecting a saving upon part of a user.

Another and equally important object 25 of the invention is to provide the device with a form of needle or stylus carriage such as will permit sliding movement of the same and the needle or stylus carried thereby longitudinally and transversely over an abrasive surface with which the device is 30 provided or in other words, affords a compound longitudinal transverse or near rotary motion, thereby facilitating the sharpening and polishing operation.

Other objects will be in part obvious and 35 in part pointed out hereinafter.

The improvements in the details and arrangement of the parts of the device will be more fully understood when considered in connection with the specific description 40 hereinafter contained and wherein a preferred embodiment of the invention is disclosed for the purpose of illustration.

In these drawings:

Figure 1 is a top plan view of the 45 sharpener,

Fig. 2 is a side elevation thereof,

Fig. 3 is a vertical longitudinal section therethrough;

Fig. 4 is an end elevation of the device, 50 and

Fig. 5 is a detail in perspective of the needle or stylus holding carriage.

Having more particular reference to the drawings, in connection with which like 55 reference characters will designate corre-

sponding parts throughout the several views, 1 represents the base or body portion of the device formed of sheet metal or other suitable material and having a longitudinally disposed elevated track or way 60 2 formed thereon intermediate its opposite sides, one side of which is slotted longitudinally for a distance of its length as indicated at 3. Ears 4 are formed on the opposite ends of this raised track 2 and serve as securing means for a sheet of abrasive material 5 such as sandpaper, emery paper or the like whereby to prevent undue shifting or movement of the paper with relation to the adjacent portion of the track. 70

Engaged over the raised or elevated track 2 is a carriage indicated in its entirety by the numeral 6 and comprising a body portion substantially U-shaped in cross section, the extremities of which are slidably engaged with those portions of the base 1 opposite the track 2. As will be noted, the forward portion of the top of the carriage 6 is recessed and is formed with a vertically disposed arm 7 carrying a needle or stylus 80 holder 8 on its upper extremity, said holder being disposed downwardly at an angle oblique to the arm 7 and being of such shape as to snugly receive a needle or stylus 9 therein. It may be noted at this particular point, that the holder 8 can be of any size or shape to correspond with the various designs or makes of needles or styluses now marketed, such as conditions or preference may dictate. The upper portion of the 90 holder is open to permit the ready insertion of the needle 9 thereinto without contact with the arm 7 and the possible damaging of the needle. Ears 10 and 11 are struck downwardly from the rear portion of the top of 95 the carriage 6, the ear 10 having its free portion bent inwardly to slidably engage the slotted side 3 of the raised track 2 while the ear 11 engages the remaining side of said raised track. It will be understood, that 100 by so connecting the carriage 6 to the raised track 2 of the base of the sharpener, that a compound longitudinal-transverse motion of the carriage with relation to the base of the sharpener will be permitted, or in other 105 words, the near rotary motion so desirable in the sharpening of various articles on abrasive surfaces can be obtained by this particular form of connection between the carriage and the raised track. However, undue dis- 110

placement of the carriage with relation to the base of the sharpener will be prevented.

In using the sharpener, a needle or stylus is engaged in the holder 8 to permit contact 5 between the lower end of the same and the abrasive sheet 5 arranged on the raised track 2. At this time, the carriage 6 is moved back and forth with relation to the base 1 longitudinally and transversely in order that 10 the lower end of the stylus will be moved over the abrasive sheet in a manner to efficiently sharpen and also polish the same, thus renewing the reproducing point thereon and in consequence allowing it to be used 15 further in the reproduction of sound waves on a record.

It may be also noted that the ears 10 and 20 11 are arranged at angles oblique to the opposite sides of the carriage and in consequence movement of said carriage transversely of the raised track 2 will be permitted. Obviously, the abrasive material 5 can be renewed as it becomes necessary.

Manifestly, the construction shown is 25 capable of considerable modification and such modification as is within the scope of

my claim, I consider within the spirit of my invention.

I claim:

A sharpening device of the character 30 described, comprising a base made from sheet metal formed with a raised flat longitudinal center portion having a slot in its side for a major portion of its length, an abrasive strip carried upon the flat raised 35 portion, a carriage made from sheet metal slideable upon the base and extended over the raised flat portion thereof, a vertically disposed arm formed on the forward end of the carriage, a stylus holder cut and bent 40 from the arm and turned downwardly at a forwardly inclined angle relative to the arm and adapted to frictionally hold stylus to be acted upon by the abrasive strip on reciprocation of the carriage, and ears cut and 45 bent from the rear end of the carriage, one ear being engaged in the slot and the other ear playing against the opposite side of the raised flat portion.

In testimony whereof I affix my signature 50 hereto.

ORRIN THOMPSON.
